US0D1010518S

(12) **United States Design Patent** (10) Patent No.: **US D1,010,518 S**
(45) Date of Patent: ** Jan. 9, 2024

(54) **MOTORCYCLE FAIRING**

- (71) Applicant: **Harley-Davidson Motor Company, Inc.**, Milwaukee, WI (US)
- (72) Inventors: **Mark Daniels**, Mequon, WI (US); **Frank Savage**, Fox Point, WI (US); **Brad Richards**, Grafton, WI (US); **Brent Ahlers**, Muskego, WI (US); **Alexander John Bozmoski**, Brookfield, WI (US); **Jeffrey Smith**, Waukesha, WI (US); **Terry Rumpel**, West Bend, WI (US); **Michael Case**, Hartland, WI (US); **Kyle Wick**, Menomonee Falls, WI (US); **Michael Carlin**, Sussex, WI (US); **Matthew Mueller**, Wauwatosa, WI (US)
- (73) Assignee: **Harley-Davidson Motor Company, Inc.**, Milwaukee, WI (US)
- (**) Term: **15 Years**
- (21) Appl. No.: **29/813,942**
- (22) Filed: **Nov. 2, 2021**

Related U.S. Application Data

CLAIM

We claim the ornamental design for a motorcycle fairing, as shown and described.

DESCRIPTION

FIG. 1 is a top, front, left perspective view of a motorcycle fairing embodying our new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a rear elevation view thereof.

The equal length broken lines in the drawings illustrate portions of the motorcycle fairing that form no part of the claimed design.
